DESIGN FOR A TRAILER

James E. Boldt, Richmond, Calif., assignor to
California Trailer Company, El Cerrito, Calif.,
a copartnership composed of Preston Perdue
and Edwin Gilbert

Application November 16, 1946, Serial No. 134,823

Term of patent 3½ years

(Cl. D14—3)

To all whom it may concern:

Be it known that I, James E. Boldt, a citizen of the United States of America and a resident of the city of Richmond, county of Contra Costa, State of California, have invented a new, original, and ornamental Design for a Trailer, of which the following is a specification, reference being had to the accompanying drawing, forming a part thereof.

Figure 1 is a view in elevation of one side of the trailer showing my new design;

Figure 2 is a view in elevation of the rear end of such trailer;

Figure 3 is a view in elevation of the other side of such trailer;

Figure 4 is a view in elevation of the front end of the trailer; and

Figure 5 is a top plan view of the trailer.

I claim:

The ornamental design for a trailer, substantially as shown.

JAMES E. BOLDT.
